UNITED STATES PATENT OFFICE.

BRUCE THOMAS UMSTED AND EDWARD NATHANIEL HARRIS, OF JACKSON, TENNESSEE; SAID HARRIS ASSIGNOR OF FORTY-FIVE ONE-HUNDREDTHS OF THE ENTIRE RIGHT TO JOHN H. JOHNSON AND SONS, OF JACKSON, TENNESSEE, A FIRM.

CURRENT RECTIFYING AND CONTROLLING SYSTEM.

Application filed April 27, 1923. Serial No. 635,164.

This invention relates to improvements in current rectifying and controlling systems and more particularly to such as are adaptable for use in systems for recharging storage batteries,—one object of the invention being to provide a system of the character specified in which the resistance coils shall be so arranged that the greatest possible number of batteries can be recharged by a 110 volt current at the same time and thus insure great economy.

A further object is to provide a rectifying and recharging system in which necessity for the use of an induction coil shall be eliminated and thus obviate difficulties incident to the use of such coil, which frequently, owing to bad connections, causes the line to stop charging while the rectifier bulb is still consuming current.

With these and other objects in view, the invention consists in certain novel features and combinations of parts as hereinafter set forth and pointed out in the claims.

In the accompanying drawings,—

Figure 1 is a front elevation of an instrument bracket or board and devices associated therewith.

Figure 2 is a rear view of the same showing the arrangement of various instrumentalities.

Figure 3 is a plan view, and

Figure 4 is a diagrammatic view.

The circuit controlling devices and connections are supported by an instrument bracket or board 1 having a rearwardly projecting shelf 2, on which latter a sheet of insulating material 2^a is secured for supporting a plurality of elements or coils 3 of a variable resistance,—six such coils being shown in the drawings. These coils are connected with each other in series and respective ends of said coils are connected by conductors 4 successively with a plurality of binding posts 5 of a segmental series of contacts 6. A spindle 7 having a knob 8 is mounted in the vertical member of the instrument bracket and carries a switch arm 9 to be moved over the contacts 6 for excluding resistance coils from or including the same in the circuit. A spring 10 may be located on the spindle 7 in such manner as to cause the switch arm to engage the contacts with yielding pressure.

A socket member 11 (such as a lamp

socket) is supported on post 12 secured to the shelf portion of the instrument bracket, (an insulating block 13 being interposed between said post and the socket member) and said member is provided with circuit terminals as is customary with lamp sockets. The 60 socket member 11 supports a rectifier bulb 14 which, in the embodiment of the invention shown in the drawings, may be of type in which anode and cathode members are located within a closed container,—two of the 65 terminals of which cooperate with two of the lamp socket terminals.

The vertical member of the instrument bracket also supports an ammeter 15 and a push button circuit closer 16 and these are included in circuits as hereinafter explained.

The leading-in conductors 17—18 of the 110 volt A. C. circuit are connected respectively with binding posts 19 and 20. The binding post 19 is connected by conductor 21 with the upper terminal of the rectifier 14 and a lower terminal of the latter is connected by a conductor 22 with a binding post 23. The binding post 23 is connected by a conductor 24 with the positive terminal of a 80 plurality of battery cells 25 and the negative terminal of the battery is connected by a conductor 26 with a binding post 27,—the latter being connected by a conductor 28 with one terminal of the ammeter 15. The other 85 terminal of the ammeter is connected by a conductor 29 with the switch arm 9 for the variable resistance or rheostat and one end of the latter is connected by a conductor 30 with the binding post 20 with which the 90 leading-in wire 18 is connected.

A loop or tap circuit is provided for exciting the rectifier 14 and two cells of the battery are utilized for this purpose,—said loop or tap circuit including the push button circuit closer 16. This circuit may be traced by a conductor 31 from the rectifier to the circuit closer 16; from the latter by a conductor 32 to a binding post 33 and from the latter by a conductor 34 to the battery 100 25 and connected with the latter at such point as to include two cells of said battery.

It has been found that with the use of a system such as hereinbefore described, we are enabled to recharge a maximum number 105 of battery cells at the same time and that great economy in the use of the charging current has been obtained. With the use

of our improvements, we are enabled to recharge any number of battery cells from 3 to at least 45.

It will be observed that our improved system does not include an induction coil and hence we are enabled to obviate difficulties encountered in charging systems employing induction coils,—such difficulties often arising by reason of imperfect connections which 10 will cause the line to stop charging while the bulb is still consuming current.

Having fully described our invention what we claim as new and desire to secure by Letters-Patent, is:

15 1. In a battery charger, comprising an electron tube having a filament and an electrode, and a battery placed in circuit with said tube and a source of alternating current, means for initially exciting the filament 20 from the battery.

2. A battery charging system, comprising an electron tube and a battery to be charged placed in circuit with a source of alternating current, said tube having a filament and 25 an electrode, and means for initially exciting said filament from the battery to be charged.

3. The method of charging a battery, which comprises connecting said battery in 30 circuit with a source of current and the electrode and filament of the electron tube, and using the charge remaining in the battery to initially excite the filament.

4. The method of charging a battery 35 from a source of alternating current through a rectifier, which comprises initiating the action of the rectifier by the charge remaining in the battery.

5. In combination, an electron tube having an electrode and filament, a battery and a main source of alternating current with 40 which said battery and tube are adapted to be placed in series circuit, and means for connecting certain cells of the battery to said filament to initially excite the same. 45

6. A battery charging system comprising a circuit, including a main source of alternating current, and a battery to be charged, and an electron tube placed in series therewith, said electron tube having a filament 50 and an electrode, a second circuit connecting certain of the battery cells to the filament, and means for making and breaking said circuits.

7. In combination, a battery to be charged 55 and a rectifying electron tube, having a filament and an electrode, means for placing said battery and tube in series circuit with a source of alternating current of relatively high voltage, and means for placing the 60 filament in circuit with certain cells of the battery to initially excite the same by a current of relatively low voltage.

8. The method of charging a battery from a source of alternating current which comprises placing said battery in series circuit with the source of current, and an electron tube having a filament and an electrode, and placing certain cells of the battery in circuit with the filament to initially excite the 70 same by the charge remaining in the battery.

In testimony whereof, we have signed this specification.

BRUCE THOMAS UMSTED.
EDWARD NATHANIEL HARRIS.
